Inventor:

Eugen Ludwig Muller
by W. K. Hechler
Attorneys.

UNITED STATES PATENT OFFICE.

EUGEN LUDWIG MÜLLER, OF BERLIN, GERMANY.

SAFETY RAZOR.

Application filed July 16, 1920. Serial No. 396,875.

(GRANTED UNDER THE PROVISIONS OF THE ACT OF MARCH 3, 1921, 41 STAT. L., 1313.)

To all whom it may concern:

Be it known that I, EUGEN LUDWIG MÜLLER, a citizen of the German Empire, residing at Berlin, Germany, have invented 5 certain new and useful Improvements in Safety Razors (for which I have filed an application in Germany May 14, 1919), of which the following is a specification.

My invention refers to safety razors and 10 more especially to the blades used in connection therewith. As is well known people with very delicate skin prefer being shaved with as rigid a razor or blade as possible. It is moreover important for such people that 15 they should be shaved at a very small angle of inclination of the razor, this being most essential for the clear shaving of concave parts of the face such as certain portions of the throat or for shaving the moustache. According 20 to the present invention now these demands are complied with by the section of the blade being given the shape of a flat roof with a hole in the middle for directly fastening the handle in the blade. In order to comply with these requirements I prefer 25 forming the blade section either like a flat triangle or like a segment.

In the drawings affixed to this specification and forming part thereof two different modifications of a safety razor embodying my invention are illustrated by way of example. In the drawings—

Fig. 1 shows a safety razor with triangle-shaped blade,

Fig. 2 a safety razor with segment-shaped blade,

Fig. 3 is a plan of the blade shown in Fig. 1.

1 is the handle, 2 the blade, 3 the protective comb. The blade is provided in the middle with a hole 5 fitted with female thread, which the handle 1 is screwed into. In the face of the blade averted from the skin a groove 6 is provided, which is deep enough to allow both blades 7 to lie flat upon the grindstone when being ground. The upper surface of the roof-shaped blade on one or both sides of the blade resembles the surface of a sphere, a cone or the like; the blade in Fig. 1 is shaped on its left half like a cone, while its right half is level. The blade in Fig. 2 is shaped like a sphere on both sides. As shown in Fig. 3, a convex

shaped edge is obtained, which offers the advantage that in shaving particularly in 55 lean faces some places may be reached better. The spherical blade offers great advantages from the manufacturer's point of view. The greatest difficulty in making rigid blades consists in the performing of the polishing 60 process, and this can be carried out to highest perfection in a sphere, as there always two faces are in touch during the polishing, while the conical shape allows of touch in a line only.

By making one half of the blade straight, the other half curved, as shown in Fig. 3, the differently curved portions of the face can be shaved equally well.

The safety razors in use till now, in which 70 a handle is screwed into the blade with the protecting comb underlying it, require special appliances for securing these parts relatively to each other in assembling them. Moreover the blade cannot easily be handled 75 in mounting and dismounting; if handled clumsily it will either slip or injure the hand. According to the present invention these disadvantages are avoided by aid of indentations 4 arranged in the blade and in 80 the protecting comb respectively. The fingers are laid in these indentations, and thus both parts are secured relatively to each other that they can be placed on the handle without using any set pins.

I claim:

1. In a safety razor apparatus, a blade having on one side, and at each edge of the blade, cutting edges offset from the main portion of the body of the blade, including 90 two plane surfaces lying in the same plane, a guard comb beneath the blade and a handle extending through a centre hole of the blade and fastened therein.

2. In a safety razor apparatus, a blade having on one side, and at each edge of the blade, cutting edges offset from the main portion of the body of the blade, including 95 two plane surfaces lying in the same plane, a guard comb beneath the blade and a handle extending through a threaded centre hole 100 of the blade and fastened therein.

3. In a safety razor apparatus, a blade having on one side, and at each edge of the blade, cutting edges offset from the main 105 portion of the body of the blade, including

two plane surfaces lying in the same plane, a guard comb beneath the blade and a handle extending through a centre hole of the blade and fastened therein, both the blade and

the guard comb being provided with wide and gently curved concavities whereby both these parts can be laid hold of by placing

the fingers in the concavities and thereby retaining them in position so that they can be fixed upon the handle without the aid of 10 projecting pins.

In testimony whereof I affix my signature.

EUGEN L. MÜLLER.
